EXPANDING TOOL FOR COLLAPSING
ANCHORING SOCKETS

George Frederick Croessant, Wyomissing, Pa.

Application March 13, 1950, Serial No. 149,417

7 Claims. (Cl. 218—19)

1

This invention relates to a tool for expanding anchoring sockets for receiving threaded bolts and of the kind disclosed in my earlier Patent No. 2,018,251 issued October 22, 1935 and in my co-pending application Serial No. 36,475, filed July 1, 1948, now Patent Number 2,559,281 granted July 3, 1951 entitled "Anchoring Socket for Bolts." In general, this type of anchoring socket, as shown in various figures of the present drawings, such as Figs. 3 and 4, comprises a tubular member whose central portion is longitudinally slotted so as to provide expansible strips, one end portion of the tubular member being threaded and in screw threaded engagement with a bolt extending through the member and the other, or head portion, being in the form of a sleeve having no threads. As disclosed in the aforesaid patent, after the threaded end portion is inserted through the hole of a supporting wall, the head of the threaded bolt is turned by a screw driver, thereby pulling the threaded inner end portion towards it, and outwardly expanding the intermediate strip portions, until finally the strip portions will become firmly anchored against the rear surface or inner wall and thereby form a solid anchor either for the threaded bolt or for eye-bolts or other supporting bolts or elements having a threaded end portion.

However, in large construction projects this mode of installation is time-consuming and considerably slower than the method disclosed in the present application.

Furthermore, in many installations, a threaded bolt as described hereinabove, is not suitable as a supporting member and instead perhaps an eye-bolt or a bolt of longer or shorter length than that which is normally included as part of the anchoring socket assembly is required to support articles on a wall or ceiling. In these instances, therefore, the threaded bolt is omitted to save cost, particularly in large scale installations where perhaps thousands of anchoring sockets are to be inserted and expanded. However, means must be provided to expand the bolts quickly and with minimum manual effort.

An object of the present invention is to provide a tool which will overcome the above-named disadvantages attendant in the use of a screw bolt for expanding an anchor socket of the type described hereinabove and disclosed in my aforesaid prior patent, which tool is easy to operate and so constructed as to allow quick expansion of the anchoring socket, thereby saving a considerable amount of time in the installation of large numbers of anchoring sockets.

2

A more specific object of this invention is to provide a tool for expanding anchoring sockets such as described in my aforesaid prior patent and pending application, which tool, by a few manual grasping operations requiring very little manual effort, will apply intermittent forces to cause expansion of the intermediate flexible strip portions of said anchoring socket and which tool is so adjustable as to permit installation of anchoring sockets of different sizes.

Other objects and advantages of the present invention will be apparent from a study of the following description, taken with the accompanying drawings wherein:

Fig. 1 is a side view of a tool for expanding sockets of the type described hereinabove and embodying the principles of my invention;

Fig. 2 is a longitudinal cross-sectional view of the expanding tool shown in Fig. 1 illustrating the tool in the open or unclamped position;

Fig. 3 is a longitudinal cross-sectional view of the forward end portion of the tool shown in Figs. 1 and 2 as applied to an anchoring socket of the type described hereinbefore and illustrating the position of the forward end portions of the tool when initially applied to the unexpanded anchoring socket;

Fig. 4 is a longitudinal cross-sectional view similar to Fig. 3 but showing the forward end portions of the tool in the operated position and showing the anchor socket in an expanded position as a consequence of operation of the tool;

Fig. 5 is a fragmentary longitudinal cross-sectional view of the forward end of the stationary handle of the tool shown in Figs. 3 and 4;

Fig. 6 is an end view of the forward portion of the stationary handle shown in Fig. 5 illustrating the V-shaped notch therein for receiving the threaded shank of the bolt;

Fig. 7 is a fragmentary, longitudinal cross-sectional view of the forward end portion of the retractable rack shown in Figs. 3 and 4;

Fig. 8 is an end view of the rack shown in Fig. 7;

Fig. 9 is a longitudinal cross-sectional view of a modified form of expanding tool embodying the principles of the present invention and wherein a circular instead of rectangular rack is used;

Fig. 10 is a transverse cross-sectional view taken along line X—X of Fig. 9;

Fig. 11 is a fragmentary, longitudinal cross-sectional view of the forward end of the tool shown in Figs. 9 and 10 illustrating the position of the tool parts and anchoring socket before operation of the tool and expansion of the anchoring socket, and

Fig. 12 is a longitudinal cross-sectional view similar to Fig. 11, but showing the tool in the operated position and the anchoring socket in the expanded position.

Referring more particularly to Fig. 1, numeral 1 denotes the relatively stationary member or handle of the tool which is substantially channel-shaped in cross-section. Handle 1 has an integral depending front end portion 2 on which is pivotally mounted by means of a pivot bolt 3 the relatively movable member or handle 4 of the tool having integrally formed, at the forward end, extensions 5 which serve as bearing support flanges for the pivot bolt 3 which straddles the width of handle 1. Integrally formed on the movable handle 4 and extending between the side flanges thereof is also a bolt or stud 6 which serves as a stop element for limiting the outward or expanding movement of the movable handle 4 with respect to the stationary handle 1. In order to limit the inward or collapsing movement of handle 4 with respect to handle 1, there is provided an adjustable stop member 7 in the form of a bolt which is screw threadedly engaged with the top web portion of handle 4. The inner end of the bolt is adapted to strike against the top of pawl 9 to arrest further downward movement of handle 4. When it is desired to obtain a greater downward stroke of handle 4, it is necessary merely to unscrew the bolt or stop member 7 to the desired extent so that the stop member will not strike the stationary handle part until a greater amount of downward movement of handle 4 has been accomplished. A helical spring 8 is provided whose upper end portion is held in place by bolt 7 and whose lower end is secured to the top portion of pawl 9 by means of a screw 10. Pawl 9 is pivotally supported by means of a bolt or pivot stud 11 secured to the vertically extending side flanges of the channel-shaped stationary handle 1.

A pivot bolt 12 is secured to and bridges the vertically extending side flanges of movable handle 4 and has pivotally mounted thereon a pawl 13. Pawl 13 is normally biased in a downward direction, as viewed in Fig. 2, by means of a helical spring 14 which has its lower end seated in a grooved or well portion formed in pawl 13 and its upper end held in a centered and fixed position by means of a screw stud or bolt 15 threaded into the top or web portion of handle 4. By means of a downward extension 4b on the forward end of the handle 4 a stop element is provided which is engageable in a correspondingly formed notch or shoulder portion in pawl 13 which limits the downward movement of pawl 13 under the action of spring 14 so as to maintain the engaging lower end of the pawl 13 close to but out of actual contact with the teeth of a reciprocable rack 16. Rack 16 is guided by the side flanges and bottom of the channel-shaped stationary member or handle 1. Secured to the rear end of handle 1 is a guide shaft 17. The forward end of guide shaft 17 is telescopically fitted in a cylindrical groove formed in the rear end of rack 16 so as to guide the rack 16 in its longitudinal movement within the stationary handle 1. A helical return spring 18 surrounds shaft 17 and has one end resting against the rear end of handle 1 and the other end in engagement with the rear end of rack 16 thus normally biasing rack 16 in a forward position, whereby its vertically extending forward end wall 16a will engage the vertically extending forward end wall 19 of handle 1. V-shaped grooves 20 and 21 are formed in the walls 19 and 16a, respectively, as

shown more clearly in Figs. 6 and 8. A V-shaped shoulder on wall 16a fits into groove 20 so as to make V-shaped grooves 20 and 21 substantially coextensive.

Fig. 3 shows the manner in which an anchoring socket of the type described hereinabove is supported in the expansion tool embodying the present invention. Generally speaking, this type of anchoring socket comprises a tubular member having an inner sleeve portion 22 which is internally threaded and in threaded engagement with a bolt 23 and, at the other end, a sleeve portion 24 which is not internally threaded and which has integral therewith a washer-like element 25, preferably provided with integrally formed wings 26 adapted to penetrate the front surface of the wall to restrain sleeve 24 from rotation when the bolt 23 is turned by applying a screw driver to the kerf of its head 27. Intermediate sleeve portions 22 and 24 are a plurality of integral, longitudinally extending strips 28, preferably having a slight outward bow at the center, or better still, at points slightly short of the central position of the strips 28 when measured from wall 29. For the exact details of construction of said anchoring sockets, reference is made to my earlier patent and my co-pending application hereinbefore mentioned.

In operation, after a hole is formed in wall or partition 29, an anchor socket and bolt is extended therethrough, as shown in Fig. 3, the bolt 23 being slightly unscrewed so as to provide a gap between the bolt head and washer-like element 25. The forward end of the tool is then applied in a manner so that the bolt shank adjacent the head is seated in V-shaped groove 21 of the forward vertically extending wall 16a of rack 16.

In operation, by manually grasping handles 1 and 4, the operator depresses movable handle 4 and causes engagement of pawl 13 with rack 16 so that upon further downward movement of handle 4, rack 16 is retracted and pulled rearwardly against the action of return spring 18, thereby effecting separation of the vertically extending end wall portions 19 and 16a of handle 1 and rack 16, respectively, as shown more clearly in Fig. 4. Thus, end wall 16a of the rack pulls on the head of the bolt, pulling with it sleeve portion 22 while end wall 19 of handle 1 abuts against washer-like element 25. The downward movement of handle 4 is arrested by adjustable stop element 7. After rack 16 is pushed rearwardly by pawl 13, the one-way acting pawl 9 will hold rack 16 in its new or partially retracted position. Then upon releasing pressure on handle 4, return spring 8 will cause upward movement thereof limited by stop bolt 6 striking against the bottom of handle 1. Then handle 4 is again depressed by grasping handles 1 and 4 together, so that pawl 13 will again engage rack 16 and push it from its slightly rearward position to a more rearward position. Pawl 9 will then hold rack 16 in its newly acquired rearward position whereupon handle 4 is again released to allow separation thereof from member 1. Then handles 1 and 4 are again grasped and further retractive movement of rack 17 is obtained and the operation is repeated until finally the desired amount of separation between vertically extending walls 16a and 19 is provided, as shown in Fig. 4, to cause full expansion of the anchoring bolt, whereby the intermediate portions of strips 28 are anchored and yieldingly held against

the inner surface of the wall 29 so as to provide a rigid and securely supported anchor.

After full expansion of the anchoring socket or expansion bolt has been attained, the rearward portion of pawl 9 is depressed so as to lift the pawl tooth and thereby release the rack 16 so that it will move forwardly under the action of return spring 18 and assume the proper position for expanding the next anchoring socket. It will be apparent that by suitable adjustment of the adjustable stop member 7, the number of strokes of the tool may be varied. For example, if it requires four grasping movements of the tool handles, that is, four intermittent or retracting movements of the rack 16, in order to effect complete expansion of the bolt from the position shown in Fig. 3 to that shown in Fig. 4, and it should be desired to reduce the number of grasping movements to say 3 or 2, this can be done merely by unscrewing adjustable stop member 7 so that when handle 4 is depressed a greater downward stroke is obtained, causing a greater rearward movement of rack 16 per stroke, therefore requiring fewer strokes for complete expansion of the anchoring socket.

A modification of the tool is shown in Figs. 9 to 12, inclusive, which is particularly suitable for installing anchoring sockets wherein threaded bolts, such as 23 described hereinabove as a component part of the anchoring socket, are not employed such as in installations where eye-bolts are preferred. Most of the elements of the tool shown in Figs. 9 to 12, inclusive, are of exactly the same construction as those in Figs. 1 to 8 and corresponding identical parts are denoted by the addition of the suffix "a" to the numeral. For example, movable handle 4a of Fig. 9 corresponds to movable handle 4 of Fig. 1, etc., therefore further description of these parts is deemed unnecessary. The principal difference in construction is that in the modification shown in Figs. 9 to 12, inclusive, a rack 30 is provided having a round cross-section as distinguished from the rack 16 which is of rectangular cross-section. Rack 30 is provided with rack teeth which extend peripherally. Integrally formed on one end of the rack 30 is a shaft or extension 31 terminating in a knurled nut 32. The rack is slidably guided longitudinally by the relatively stationary handle 33 which has a substantially U-shaped cross-section, as will be more apparent in Fig. 10. Movable handle 4a is pivotally mounted on the stationary handle 33 by means of a pivot bolt 34. At the opposite or forward end of rack 30 there is screw threadedly engaged a removable extension 35 which is held stationary with respect to the rack by means of a set screw 36 or other suitable detachable securing means. The opposite end of extension 35 is also screw threaded and is engageable with the internally threaded sleeve portion 22 of the anchoring socket as shown more clearly in Figs. 11 and 12. The purpose of the extension 35 is to provide for different thread diameters of threaded sleeve portion 22 since for different uses, different sizes of anchor bolts are required. That is to say, while the threaded portion of extension 35 which is engaged in rack 30 is always of the same diameter, the opposite threaded portion can be made of different diameters by enlarging the diameter of that end portion.

In operation the forward vertically extending wall 37 of stationary handle 33 is placed in juxtaposition to the washer-like element 25 of the anchoring socket. Then by turning the knurled

nut 32, pawl 9a being held out of engagement with the rack teeth, the forward screw threaded end of extension 35 is screw threadedly engaged to sleeve portion 22, pawl 9a being then released.

5. The handles 33 and 4a are grasped and released a number of times so as to obtain step-by-step retractive movements of the rack 30. Pawl 9a will, at the end of each retractive movement, hold the rack in its new position so that after a number of downward and upward strokes of handle 4a with respect to handle 33, the forward end parts of the tool will move from the position shown in Fig. 11 to that shown in Fig. 12 whereby the anchoring socket will become fully expanded.
10. Thereafter, pawl 9a is released, allowing the return spring to push rack 30 forwardly from the position shown in Fig. 12 to that shown in Fig. 11 to prepare the tool for installation of the next anchoring socket. The operation is otherwise identical to that of the tool shown in Figs. 1 to 8, inclusive, and described in full hereinbefore.

Thus it will be seen that I have provided a highly efficient tool for expanding anchoring bolts or expansion sockets, either of the type described in my aforesaid patent or co-pending application or useful for expanding other types of expansion bolts or similar articles. Also, it will be seen that I have provided a tool which greatly shortens the time required for installation of large numbers of anchoring sockets, and greatly facilitates expansion of these sockets since operation of the tool requires a minimum amount of manual effort to expand the anchoring sockets.

35. While I have illustrated and described several embodiments of my invention, it will be understood that these are by way of illustration only, and that various changes and modifications may be made within the contemplation of my invention and within the scope of the following claims.

40. I claim:

1. A tool for expanding expansion sockets, said tool comprising a pair of handles pivotally connected together at one end thereof, a spring interposed between said handles for normally spreading them apart, stop means on one of said handles and adapted to abut the other for limiting the spreading apart movement of said handles, one of said handles having an upstanding wall portion at the forward end thereof having a slot, a retractile member also having an upstanding wall portion at the forward end thereof having a slot which is of substantially the same size and in registry with said first mentioned slot and being slidably mounted within said last mentioned handle, and means for translating pivotal movement of said handles towards each other to retractive movement of said slideable member so as to effect separation of said forward wall portion and the forward end of said retractile member and thereby cause expansion of the expansion socket.
45. 2. A tool for drawing together the end sleeve portions of an expansion socket and outwardly collapsing its central, longitudinally extending strip portions, comprising a pair of handles pivotally connected to each other at one end, a spring interposed between said handles for normally spreading them apart, stop means on one of said handles and adapted to abut the other for limiting the spreading apart movement of said handles, one of said handles being substantially channel-shaped in cross-section and having an upstanding front end wall portion which includes a slot, a rack longitudinally slidably and guided

60. 65. 70. 75. by said last mentioned handle and having a front

upstanding wall portion including a slot of substantially the same size and in registry with said aforesaid front end wall slot of the handle, and means mounted on said handle members for effecting step-by-step retractive movement of said rack upon collapsing movement of said handles whereby one of said wall portions will hold one end portion of the expansion socket stationary while the other wall portion will, by means of a threaded bolt head supported in its slot, move the other end of said expansion socket, to which it is threaded, towards the first mentioned end to effect expansion of the intermediate strip portions of the socket as the result of separation of said forward end wall portions.

3. A tool for expanding an anchoring socket of the type having two sleeve-like end portions, one of which is internally threaded, and integral intermediate strip-like portions, and having a bolt threaded to one sleeve-like portion and extending through the other unthreaded sleeve-like portion, which tool comprises two hollow handles pivotally connected together at one end thereof, a spring interposed between said handles for normally spreading them apart, stop means on one of said handles and adapted to abut the other for limiting the spreading apart movement of said handles, a relatively stationary handle having a longitudinally reciprocable rack therein, an upstanding wall portion at the pivotal end of said handle including a substantially V-shaped notch at the top thereof, the forward end of said rack including a second upstanding wall portion having a substantially V-shaped slot in registry with said notch and wherein the threaded shank near the head portion of said bolt may be seated, the other handle being relatively movable, a pawl pivotally mounted on said last named handle and adapted to engage said rack intermittently as the result of pivotal movement together of said handles, whereby said upstanding end wall portions of said stationary handle and rack are separated causing pull of the threaded sleeve-like portion of said anchoring socket towards the unthreaded and sleeve-like portion thereof and thus expanding the intermediate strip portions of the anchoring socket against a supporting wall.

4. A tool for expanding anchoring sockets of the type having sleeve-like ends, one of which is internally threaded, and intermediate interconnecting longitudinally extending strips, which sockets are adapted to be inserted through a hole in a supporting wall, said tool comprising a pair of handles pivotally interconnected at one end thereof, one of said handles having an upstanding wall at one end thereof including a slot, a longitudinally reciprocable rack contained in said one handle, a return spring for normally urging said rack so that its forward end will normally abut against said upstanding end wall portion, a pawl pivotally mounted on the other handle, a stop member forming a part of said other handle adapted to abut against said one handle, a return spring connected between said pawl and said other handle for normally urging said pawl against a stop portion of said other handle to bring the tooth of the pawl into position for engaging the teeth of said rack, a second pawl pivotally mounted on said one handle, a return spring having one end in engagement with said second pawl and the other end secured to said other handle so as to normally bias said second pawl into engagement with said rack, said upstanding wall portion being adapted to be held against a stationary unthreaded sleeve-like end

of said anchoring socket, the forward end of said rack being connected to the internally threaded sleeve of said socket so that upon each collapsing pivotal movement of said handles, a partial retractive movement of said rack will result to provide a step-by-step expansion force to said anchoring socket.

5. A tool as recited in the preceding claim wherein said rack is provided with an upstanding end wall portion with a slot adapted to come into registry with said aforementioned slot, said slots being adapted to receive a threaded shank portion of a bolt whose end is screw threaded to the internally threaded sleeve-like end of said expansion socket.

6. A tool for expanding an anchoring socket of the type having sleeve-like end portions and integral longitudinally extending intermediate strip portions and a bolt whose end is screw threaded to one of said sleeve-like portions and extends through the other, said tool comprising a pair of handles pivotally connected together at one end thereof, a reciprocable rack slidably mounted and guided longitudinally by one of said handles which acts as a stationary handle, the forward end of said stationary handle having an upstanding wall with a slot at the top thereof, said rack being substantially cylindrical, having peripherally extending rack teeth, a return spring whose ends are urged against one end of said rack and of said stationary handle so as to normally bias the other end of the rack into engagement with said upstanding wall portion, the other handle being relatively movable, a pawl being pivotally mounted on said relatively movable handle and being normally spaced from said rack, said pawl adapted to engage said rack as the result of pivotal movement together of said handles, means for holding said rack in any given retracted position, an extension secured to the forward end of said rack and having a threaded end which is screw threadedly engageable with the internally threaded sleeve-like portion of the anchoring socket, a knob integrally connected to the other end of said rack, whereby said rack is turnable within the stationary handle so as to screw or unscrew said extension in or out of said threaded sleeve-like portion of the anchoring socket.

7. A tool as recited in the preceding claim wherein said means for holding the rack in a retracted position comprises a pawl pivotally mounted on said stationary handle and a bolt screw threaded to the movable handle and a spring having one end in engagement with said last mentioned pawl and the other end surrounding the threaded portion of said bolt whereby said bolt acts as an adjustable stop member for limiting the amount of collapsing movement of said handles when drawn together by virtue of striking of the end of said bolt against said last mentioned pawl.

GEORGE FREDERICK CROESSANT.
